UNITED STATES PATENT OFFICE.

GEORGE ERNEST WARD, OF BROCKTON, MASSACHUSETTS, ASSIGNOR TO GEO. E. KEITH COMPANY, OF BROCKTON, MASSACHUSETTS, A CORPORATION OF MASSACHUSETTS.

SOLE STAMPING AND SLITTING MACHINE.

REISSUED

No. 921,573.

Specification of Letters Patent.

Patented May 11, 1909.

Application filed June 25, 1908. Serial No. 440,349.

To all whom it may concern:

Be it known that I, GEORGE ERNEST WARD, of Brockton, in the county of Plymouth and State of Massachusetts, have invented certain new and useful Improvements in Sole Stamping and Slitting Machines, of which the following is a specification.

This invention has for its object to provide a machine for stamping and slitting inner soles, the term "slitting," as here used, meaning the formation of short transverse slits at the heel portion of an inner sole, said slits defining the rear end of the flap or lip formed by channeling the edge of the forepart of the inner sole. Slitting machines for this purpose are now in use, the machine including a bed which supports the heel portion of an inner sole, a head which is movable toward and from the bed, and carries a pair of knives adapted to form two slits or cuts in one side of the inner sole, said cuts forming the rear ends of the channel flap or lip, and mechanism for reciprocating the head to cause the knives to act on a sole supported by the bed.

My invention is chiefly embodied in adding to a machine of this character, parts comprising a stamping die forming a support for a portion of the inner sole, and located in suitable relation to the bed of the slitting machine, a plunger movable toward and from said die, and adapted to press the sole against the die, the latter being formed to impress on the inner sole a suitable design, such as the stamp of the Boot and Shoe Workers' Union, and the number of the factory where the machine is employed, and mechanism suitably connected with the mechanism which actuates the slitting machine, whereby the stamping plunger is reciprocated simultaneously with the cutter-carrying head of the slitting machine, so that the two operations, namely: the slitting and the stamping of the inner sole, are carried on simultaneously, and much less time is required than would be involved if the slitting and stamping operations were performed separately.

Of the accompanying drawings, forming a part of this specification,—Figure 1 represents a side elevation of a machine embodying my invention, consisting of a slitting machine to which my improvements are connected. Fig. 2 represents an end eleva-

tion of the same. Fig. 3 represents a side view of an inner sole showing the slits and the union stamp formed simultaneously thereon by the conjoint operation of the slitting machine, and of my improved attachment.

The same reference characters indicate the same parts in all the figures.

In the drawings, 12 represents the sole-supporting bed of a slitting machine of suitable construction, and 13 represents a head which is movable toward and from the bed 12, and carries a pair of slitting knives 14, adapted to form two transverse slits 15, 15, in one side of an inner sole 16, said slits being so located as to define the rear ends of a lip, the main portion of which is formed by channeling the edge of the forepart of the inner sole. The head 13 usually carries, in addition to the slitting knives 14, suitable means for forming marks or indentations 18 between 75 and in alignment with the slots 15, said indentations being used to guide the operator in applying the welt to the inner sole.

The means here shown for reciprocating the head 13 comprise a walking beam 19 fulcrumed at 20 in the standards 21 rising from a base 40, one arm of said walking beam having a suitable engagement with the head 13, and a cam 22 mounted upon a shaft 23 which is journaled in bearings in the supporting frame 21, said cam engaging the other arm of the walking beam 19 in such manner that its rotation imparts an oscillating motion to the walking beam.

Since my invention does not relate to the specific construction of the slitting machine, I have not attempted to show the latter in detail.

In carrying out my invention, I provide as an addition a slitting machine of the general character above stated, a stamping mechanism adapted to impress on the shank part of the inner sole a design 24, which is indented in the material of the inner sole, and may constitute what is known as the union stamp 100 of the Boot and Shoe Workers' Union, and the number of the factory. In all shoe factories employing so-called union help, it is the rule to apply such a design or stamp to the inner surface of the inner sole in such position that 105 it will be visible in the completed boot or shoe. Heretofore, this stamp has been applied by a die or stamp held by the operator,

and applied by means of a hammer or mallet,—an operation which involves a considerable expenditure of time. My invention, hereinafter described, obviates this lost time, and enables the union stamp to be applied to one surface at the same time that the slits 15 are cut in from the other side of the inner sole.

The stamping mechanism of my invention 10 includes a stamping die 25 which is movable vertically in a fixed guide 26, and is yieldingly supported by a spring 27 in said guide, the die being arranged to bear on the under side of an inner sole 16 at a suitable distance 15 from the bed 12 of the slitting machine. Coöperating with the stamping die 25 is a hammer or plunger 28, which is movable in a fixed guide 29, and is reciprocated in said guide by mechanism hereinafter described, 20 the arrangement being such that when the hammer is moved downwardly toward the sole, it presses the under side of the sole against the die 25, and thus causes the latter to impress the stamp or design 24 in the 25 under side of the sole, the side opposite that which receives the guide markings 18.

The shank of the plunger 28 is engaged with one arm of a walking beam 30, which is fulcrumed at 31 between fixed vertical standards 32 forming extensions of the standards 21. One arm of the walking beam has an opening which receives the shank of the plunger 28, portions of the arm forming the sides of said opening being provided with 35 slots 33, which are slightly elongated lengthwise of the walking beam, and receive studs or trunnions 34, projecting laterally from opposite sides of the shank of the plunger 28, a suitable connection being thus formed between 40 the walking beam and the plunger, which compensates for the swinging movement of the walking beam, and permits a rectilinear movement of the plunger. To the opposite arm of the walking beam is pivoted 45 at 35 a link or rod 36 attached to a strap 37, which surrounds an eccentric 38 affixed to a shaft 39 journaled in bearings supported by the base 40, which also supports the standards 32, the stamping die guide 26, and the plunger guide 29. The base 40 also supports the slitting machine, the frame 21 of 50 said machine being detachably secured by bolts 41, or otherwise, to the base 40.

A suitable connection is provided between 55 the mechanism which reciprocates the hammer 28, and the mechanism which reciprocates the slitting knife carrier or head 13, so that said parts are operated simultaneously. As here shown, the said connection comprises a gear 42 affixed to the shaft 39, and a gear 43 affixed to the shaft 23, and meshing with the gear 42. Power may be applied to either of the shafts 39 or 23, preferably to the shaft 39, which may be provided with a driving 60 pulley engaging a driving belt.

It will be seen that the rotation of the shaft 39 causes the simultaneous operation of the slitting knife head, or carrier 13, and the hammer or plunger 28, so that an inner sole 16 applied to the bed 12 and die 25, as indicated in Fig. 1, is provided at one operation with the slits 15, and with the stamp 24. It will be seen, further, that the base 40 serves to support not only the stamping mechanism, but also the slitting mechanism, said 75 bed, the driving shaft 39, the stamping die 25, the plunger or hammer 28, the fixed guides for the stamping die and hammer, the connection between the hammer and the driving shaft, and the standards 32 for the 80 walking beam, forming a part of said connection, constituting a stamping attachment to which the slitting machine may be applied.

Slitting machines are now on the market in which the shaft 23, carrying the cam which actuates the walking beam 19, is provided with a driving pulley engaged with a driving belt. Such a machine requires for its use as a part of my improved machine, only the removal of the driving pulley, and the substitution therefor of the gear 43. It will be seen, therefore, that to construct a machine complete according to my invention, a slitting machine of known make may be utilized without change or modification of the latter, 95 excepting the slight modification above described.

The walking beam 30 is above the walking beam 19, and of greater length, both being supported by the uprights 21 and extensions 100 32 thereof. This provides a compact and convenient machine for the simultaneous stamping and slitting, enables the stamp to be applied always in proper position relatively to the slits 15 and guide markings 18, 105 and provides for a simple arrangement of gearing and connections for operating the knives and plunger 28.

The die 25 and the hammer 28 constitute opposed sole-stamping members, one of 110 which is yieldingly supported or backed to permit the stamping of relatively thick soles without undue strain on the machine. It is obvious that a yielding backing, such as that afforded by the spring 27, may be applied to 115 the hammer instead of to the stamping die. The hammer guide 29 is here shown as a neck or cross bar connecting two uprights 290, which are secured to the base 40. An additional guide for the stamping die may be 120 formed in a cross bar 291 between said uprights. The bed 12 and the knife-carrying head 13 constitute opposed sole-slitting members arranged in operative proximity to the stamping members, there being, therefore, two pairs of members, one for stamping, and the other for slitting, one member of each 125 pair being movable toward and from the other, mechanism being provided for simultaneously reciprocating the two movable 13

members. The gear 42 on the driving shaft 39 is a member adapted to engage the operating mechanism of the sole-slitting members of the machine.

5 I claim:

1. A sole stamping and slitting machine, comprising a base, standards thereon, two walking beams supported one above the other by said standards, means for oscillating said beams in unison, and sole slitting and stamping members connected with said beams.

10 2. A sole stamping and slitting machine, comprising a base, standards thereon, a sole supporting bed and a die supported by said base, two walking beams supported one above the other by said standards, means for oscillating said beams in unison, sole slitting knives carried by one beam, and a plunger

carried by the other beam to coöperate with 20 said die in stamping a sole.

15 3. A sole stamping and slitting machine, comprising a base, standards thereon, a sole supporting bed and a yieldingly mounted die supported by said base, two walking beams 25 of different lengths supported one above the other by said standards, means for oscillating said beams in unison, sole slitting knives carried by one beam, and a plunger carried by the other beam to coöperate with said 30 yielding die in stamping a sole.

In testimony whereof I have affixed my signature, in presence of two witnesses.

GEORGE ERNEST WARD.
